F. KANDEL.
SOLDERING DEVICE.
APPLICATION FILED JAN. 30, 1915.

Patented May 11, 1915.

Fig. 1.

UNITED STATES PATENT OFFICE.

FRED KANDEL, OF WILKINSBURG, PENNSYLVANIA.

SOLDERING DEVICE.

1,138,760.

Specification of Letters Patent.

Patented May 11, 1915.

Application filed January 30, 1915. Serial No. 5,322.

To all whom it may concern:

Be it known that I, FRED KANDEL, a citizen of the United States, residing at Wilkinsburg, in the county of Allegheny and State of Pennsylvania, have invented 5 certain new and useful Improvements in Soldering Devices, of which the following is a specification.

The present invention relates to new and 10 useful improvements in soldering irons.

The primary object of the invention is the provision of a soldering iron, so constructed that the same is self heating, and which can be quickly heated, without necessitating 15 placing the same in the usual furnace.

Another object of the invention is the provision of an iron of the above specified character, which is so constructed that the various parts thereof can be quickly 20 removed and replaced in case of wear or for any other reason.

A further object of the invention is to improve and simplify devices of this character, rendering them comparatively simple and 25 inexpensive to manufacture, reliable and efficient in use, and readily operated.

With the above and other objects in view, the present invention resides in the certain 30 novel features of construction, formations, combinations, and arrangements of parts to be hereinafter more fully described, claimed and illustrated in the accompanying drawing, forming a part of this application, it 35 being understood in this connection, that various minor changes in the specific details of construction can be resorted to within the scope of the appended claim, without departing from the spirit or sacrificing any of the advantages of the invention.

40 In the accompanying one sheet of drawing, Figure 1 is a longitudinal sectional view, taken through my improved soldering iron; and Fig. 2 is a transverse sectional view, taken on the line $\alpha-\alpha$ of Fig. 1.

45 Referring to the accompanying drawing by corresponding characters of reference, to indicate like parts throughout the several views, the numeral 5 designates in general my improved soldering iron, which consists 50 of a hollow handle 6, a heating head 7 and a tubular body portion 8, having spaced series of apertures 9 and 10, to permit the entrance of air into said body portion 8. The handle 6 is preferably provided with a removable end 11, which permits access to

the same, while the opposite end thereof has a suitable filling opening 12, and a threaded opening 13, which latter has threaded engagement with the outer end of a pump which is shown in conventional form as 60 at 14.

A pipe 15, leads from the hollow handle 6, through the tubular body portion 8, to a point adjacent the head 7, this said pipe containing cotton or the like as at 16, whereby the fuel passing from the handle 6, will be strained, while being forced through the said tube or pipe 15, by means of air under pressure supplied by the pump 14. The inner or forward end of the pipe 15 has a 70 downwardly inclined inlet nozzle 17, while the same is held against any undesired movement, by the support 18, which may be of any character. This pipe 15 is preferably upset at its forward end as at 19 in 75 advance of which the fuel is vaporized and discharged through the nozzle 20, positioned adjacent the inner end of the head 7. The flow of fuel through the pipe 15 is controlled by the valve 21. The head 7 is formed with 80 a central bore 22, terminating short of the tapered outer end thereof and connecting with the rearwardly extending branches 23, which lead through the head adjacent the outer surface thereof, providing a means for 85 quickly heating the same, at the expense of but very little fuel.

From the foregoing it will be manifest that a soldering iron is provided, which will fulfil all of the necessary requirements of 90 such a device.

Having thus fully described this invention, what I claim as new and desire to protect by Letters Patent is:

In a soldering device such as described, a 95 hollow handle, a removable closure for one end of the handle, a support conforming to the shape of the interior of the handle and engaging the removable closure for the end thereof, a tubular body portion having one 100 end engaged by the removable closure and secured thereto and extending outwardly from said hollow handle, a head secured to the opposite end of the tubular body portion, said head having a central rearwardly 105 extending passage therein and supplementary passages leading from the forward end of the central passage to the rear of said head and opening through the outer sides thereof, a partition disposed within 110

said tubular body and having an opening therein, a pipe supported by said partition and by the first mentioned support, said pipe having its rear end curved downwardly 5 into the hollow handle and an offset portion at its opposite end terminating in a depending discharge nozzle, a valve controlling the passage of fuel through the pipe and means for forcing air under pressure into the hol-

low handle for the purpose of forcing fuel 10 from the hollow handle through said pipe.

In testimony whereof I affix my signature in the presence of two witnesses.

FRED KANDEL.

Witnesses:

HENRY BEELER,
ARTHUR FILBY.
